United States Patent Office.

A. N. PARKHURST, OF KNOXVILLE, ILLINOIS.

Letters Patent No. 96,475, dated November 2, 1869.

IMPROVEMENT IN PUMPS.

The Schedule referred to in these Letters Patent and making part of the same.

To all to whom it may concern:

Be it known that I, A. N. PARKHURST, of Knoxville, in the county of Knox, and State of Illinois, have invented a new and useful Improvement in Pumps; and I do hereby declare that the following is a full, clear, and exact description of the construction and operation of the same, reference being had to the accompanying drawings, making a part of this specification, in which—

Figure 1 is a perspective view.

Figure 2 is a vertical section.

Figure 3 is a view, in detail, of collar.

Figure 4 is a view, in detail, of the clamp.

Like letters in the figures of the drawings indicate like parts.

My invention is intended as an improvement upon that patented by me February 10, 1863. I construct the stock or top A of the pump of a similar form and material as in that, the cylinder or chamber B being separate, and made of stone-baked clay, glazed or vitrified in the interior, and having flanges d d at the upper and lower ends thereof, by which it is united to the pump-stock above, and to a metallic collar, C, with flange e below, which collar is driven on to the tubing D, the latter forming the upper termination of the wooden tubing or pipe, by means of bolts f through the flanges d e.

Having thus given a general outline of the construction of this pump, as improved, I will proceed with a detailed description of it.

The chamber or cylinder B is of the same material and shape as before described, its flanges d d being pierced with a sufficient number of holes to receive bolts e e and f f, uniting it with the stock A.

Around the base of the latter are placed two or more clamps b, with a claw, k, at the upper end of each, which bite into the wood of the stock, and are further secured to the same by means of several screws.

Each of these clamps terminate below, near the base of the stock, in horizontal projecting jaws i i, which receive the bolts e, by which the connection is made to the cylinder, through the perforations in the flanges thereof, as before described, rubber or other appropriate packing being placed between the joints of the stock and chamber.

To connect my tubing (of wood) with the chamber or earthenware cylinder, I construct a collar, C, of metal, of a bore about the size of that of the cylinder, and having a flange, e, which corresponds with and is bolted to the flange d of the former.

I make the tube of the collar about four inches deep, or deep enough to form a sufficient hold, when driven on to the end of the wooden tubing, the bottom edge, on inside of collar, being tapered, so as to wedge itself tightly on to the wooden tubing, the top of the latter forming the valve-seat g, at or near the junction of the collar and chamber.

The flanges e of the collar are united to that of the chamber B by bolts f and nuts, with the usual packing at the joint.

The lower edge of the tube of collar is strengthened, by means of an enlargement of the metal, in the shape of an annulet, m, on its outside.

The piston or bucket is of any simple construction, and the same as described in my original patent.

The improvement sought to be accomplished by this construction of pump is, first, the attaching of a metal collar, C, with flange, for connections to the upper end of the wooden piping, in order to furnish a more ready and convenient place of connection or division of the pump at the insertion or point of location of the valve, an important desideratum in pumps of all kinds, by which facility of examination of the valve is presented.

Secondly, the doing away with the weight and expense of heavy cast-iron flange, by which the pump and tubing was hung to the platform of the cistern or well, this mode of construction enabling the pump to rest on the bottom of well or cistern, and steadied by the square part of the stock, so that farmers, and others unacquainted with these articles, may take them apart, and examine the valves, and adjust any damage, with much greater facility than pumps of any other construction at these points.

Thirdly, the clamps b b, which supersede the combined long clamp-bolt used in my first patent, above mentioned, and forming a stronger, simpler, and cheaper coupling of the stock to the chamber.

Fourthly, this construction of pump is much more economical and simpler, both in placing in position, as in removing it, or repairing it, and is also much cheaper to make, saving as much as two dollars in the construction of each pump.

Claim.

Having thus fully described my invention,

What I claim therein as new, and desire to secure by Letters Patent, is—

The baked-clay chamber B, having its upper end united to the stock A by clamps b, provided with open jaws i i, to receive the bolts, and its lower end, or base, united to the collar C, having its lower interior edge tapering, and provided on its outer edge with the annulet m, when the said collar is arranged and driven on the stock D, so that the main connection of the pump may be made at the point of location of valve g thereon, substantially in the manner and for the purpose as shown and described.

In testimony that I claim the foregoing, I have hereunto set my hand, this 12th day of May, 1869.

A. N. PARKHURST.
